UNITED STATES PATENT OFFICE.

RICHARD MOLDENKE, OF WATCHUNG, NEW JERSEY.

ART OF CASTING.

Application filed September 1, 1922. Serial No. 585,590.

To all whom it may concern:

Be it known that I, RICHARD MOLDENKE, a citizen of the United States, residing at Watchung, in the county of Somerset and State of New Jersey, have invented certain new and useful Improvements in the Art of Casting, of which the following is a specification.

This invention relates to the art of casting metals and while not restricted to use in connection with the casting of any particular metal is especially intended to enable the production of accurately dimensioned castings of all kinds.

15 The automatic molding machine which is now extensively used in foundries has greatly increased foundry production and has also, in a measure, reduced the manual labor of the operative along certain lines, but has increased his labor along other lines. Whereas a man might formerly make by hand labor, say 100 molds daily, and he had the added labor of parking the molds over some considerable space and eventually carry iron to pour them off, today he makes probably 300 of the same molds by machine, and while the heavy work of ramming up sand has been almost entirely eliminated, he has now to park molds and carry iron three times the dead weight, as well as walk three times as far back and forth as was formerly the case. Hence the continued avoidance of our youth of apprenticeship in the foundry and the difficulty of holding molders.

25

The object of the present invention is to overcome much of this labor handicap and to moreover produce a simple, highly efficient and thoroughly practical casting mold adapted to take the place of the ordinary flask systems embodying a cope and drag clamped together and housing the tamped or rammed sand.

A further object of the invention is to so construct the mold that it is adapted to house just sufficient sand as is necessary to properly form the mold cavity and to fill out the confines of the mold with spacing or filler members which entirely surround the sand in which the mold cavity is formed and are so constructed that when the mold is closed, the spacing elements will be firmly held together and will in turn maintain the cavity forming sand in proper condition and positioned against in-

advertent shifting and ferrostatic pressure developed during the pouring.

Another object of the invention is to so construct the filling or spacing elements that they may be made of metal or other suitable substance in such manner as to properly vent the mold cavity and to so shape and proportion these filler elements that they are adapted for repeated use in such numbers and combinations as may be required in casting different shapes.

The container portion of this invention, which corresponds to the flask of the prior art, is preferably so constructed that the cavity forming sand and filler elements may be built up or assembled in substantially complete form and the container parts thereafter set up about the finished assembly and tightly clamped together for the purpose of enabling the entire construction to be handled as a unit and at the same time to firmly hold all the component parts in tightly assembled condition.

The cavity forming sand referred to is preferably either prepared molding sand for dry-sand work, or a core-sand mixture. In practising the invention, this sand is preferably rammed or formed into the desired shape or shapes to form the mold in the core room of the foundry, just sufficient sand being used to properly house the mold cavity or cavities and this having been accomplished, the sand elements thus formed are treated in any suitable manner as by baking to render them easily transportable.

In fact, it is highly practical to construct these sand elements in the same manner now generally practised for the making of cores, which are formed, baked and laid aside until used. By thus minimizing in the sand or sand mixture employed, the sand elements are kept at a minimum thickness necessary to effectively and safely hold the molten metal, and also at a minimum weight; and the work of making them can be easily carried on at a bench, the operatives remaining seated during the operation, in contradistinction to the heavy and laborious task of making sand in a flask about patterns. In the majority of instances, patterns are not required in making the sand elements of this invention, they may be simply rammed or otherwise formed in suitable core-boxes, this latter course being preferable for quantity production.

After the sand elements have been constructed in the manner described, they are positioned in the mold of this invention and the intervening space between the sand elements and the interior faces of the mold are filled with filling elements of which a large variety of sizes and shapes may be employed. The particular filler elements used may be decided upon by the engineering corps of the foundry which gives a relatively unskilled workman instructions as to what filler blocks are to be used by numbers. The relatively light finished sand elements can thus be transported readily to the casting room and there assembled by unskilled help, enclosed in the container parts, clamped and the pouring proceeded with.

Features of the invention, other than those specified, will be apparent from the following detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a longitudinal section through a mold embodying the present invention, said section being taken in the plane of line 1-1 of Figure 2.

Figure 2 is a view taken on the broken line 2-2 of Figure 1, showing the right hand half of the mold of Figure 1 in plan and the left hand half of such mold in section.

Figure 3 is a fragmental section of one of the end plates of the mold.

Figure 4 is a fragmental face view of the interior of the plate shown in Figure 3; and,

Figure 5 is a perspective view of one of the filler members illustrated in Figures 1 and 2; and,

Figure 6 is a section perspective of two cooperating sand sections forming a mold cavity.

The mold of the present invention instead of embodying the usual cope and drag as heretofore is preferably constructed of four wall elements, which collectively constitute a box-like structure or container in which the sand and associated filler elements are housed. The box-like structure referred to comprises six wall elements, of which 1 designates the bottom, 2 the top 3 and 4 the ends and 5 and 6 the sides.

In practice, these wall elements may be made in the form of castings suitably cored out or ribbed to minimize weight, but to produce a strong and rigid construction. The inner faces of each of the walls, which are presented to the filler elements being made perfectly flat and preferably in the

form of true plane surfaces. Those portions of the walls, however, which come into abutting relation with adjacent walls are angularly disposed with reference to the plane faces of the box-like interior for the purpose of facilitating the assembly of the parts. For example, the four marginal portions of the inner face of each end wall 3 and 4 are sloped as shown at 7 in Figures 1, 2 and 3, while the four edges of the two sides 5 and 6 are similarly sloped as shown at 8 in Figure 2. In a similar manner, the two opposite ends of each of the bottom and top 1 and 2 are likewise sloped or bevelled as shown at 9 in Figure 1. As a result of this construction, it will be apparent that if the top and bottom walls are positioned between the two end walls, as shown in Figure 1, and pressure is applied to the two end walls to force them in a direction toward one another, the sloped or bevelled edges 7 and 9 of the respective parts will result in a wedging effect and which will tend and in practice actually force the bottom and top 1 and 2 in a direction toward one another.

In like manner, the formation of the side walls 5 and 6 with their beveled edges 8 will also bring about the same result. That is to say, the drawing of the two ends 3 and 4 together will simultaneously force the side walls 5 and 6 toward one another. It will therefore be apparent that if all of the walls of the mold are assembled and the end walls thereafter forced in a direction toward one another by clamps or other suitable means, the four longitudinal walls of the resulting box-like structure will be forced inwardly by the wedging action referred to and have a compressing effect upon the contents of such box-like construction, so that such contents will be forced into compacted condition.

In accordance with this invention, the box-like structure referred to is adapted to contain and house sand elements of less dimensions than the interior dimensions of such structure, the intervening space being filled out by filler or spacing members.

In practice, the mold cavity is formed in sand elements which may be molded of ordinary molding sand, but are preferably of prepared molding sand for dry sand work or a core sand mixture, these various mixtures and prepared molding sands being well known in the prior art and particularly used for the making of cores. I employ this character of sand element in order to enable the mold cavities to be made, finished and baked in a room especially intended for this purpose, such, for example, as the core room of a foundry, there to be laid aside or stored until required for use. The making of these sand elements is accomplished independently of the box-like

mold structure referred to and may be made in the same way as cores have been heretofore constructed.

This manner of producing the sand elements entirely eliminates the arduous and slow task of tamping molding sand directly within a mold to be left therein for casting. In making the sand elements in accordance with this invention, they are made as stated 10 in the core room or otherwise without the employment of the wall members of the mold and are constructed as lightly as practical, the walls of the sand elements being of just sufficient thickness, as is necessary to 15 give them body and preclude the passage of the excessive heat of molten metal therethrough.

This method of making the sand elements permits of a degree of accuracy which cannot 20 possibly be obtained through the prior tamping methods, since such elements may be made in steel dies, as used in die casting processes, and which will assure of absolute accuracy. The use of dies in the making of 25 the sand elements is particularly applicable when quantity production is desired and has the advantage of producing such accurate castings that subsequent machining operations are rendered unnecessary. The accuracy 30 of die casting is approached very closely when castings are made in sand elements constructed as described and employed in the mold of this invention.

In the accompanying drawings, several 35 sand elements made in the manner described are illustrated and bear the reference character 10. They are shown as positioned within the box-like structure of the mold, while the intervening space between the 40 sand elements and the inner confines of the mold are filled out with filling or spacing blocks 11. These filling and spacing blocks are in practice provided in assorted sizes and shapes, so as to permit the filling out of 45 the mold through the employment of appropriate filler blocks. I find it highly practical to number the blocks or otherwise designate them, so that the engineering department of the foundry can, in the office, determine 50 what blocks are to be employed in conjunction with any particular casting job and a diagram may be furnished to the workman showing the blocks by numbers, so that he is simply required to go to the store-room, get the blocks by numbers and assemble 55 them as shown in the diagram. No skill is required for this work and the cost of casting as heretofore practiced through the employment of highly skilled workmen is 60 minimized in the manner specified.

Figures 1 and 2 illustrate very clearly how a plurality of sand elements may be assembled to permit the pouring of several castings at one operation. The top wall 65 element 2 of the mold is preferably provided

with one or more pouring openings 12, each of which is adapted to be associated with a pouring basin 14, preferably comprising two sections which interlock with the top wall as shown and are held in assembled relation 70 by means of a wedge ring 15. The pouring basin 14 is lined with a suitable refractory material 16, which, in practice, may be of molding sand, core sand or a molding sand mixture and may be made in the same manner as the sand elements 10 referred to. The molten metal is conveyed from each pouring basin 14 through sand elements 17 and 18 constituting sprue sections to the runner 19, which is formed between adjacent sand elements 10. The runner 19 in each case is shown as extending transversely of the mold and from the lateral edges of said runner the several cavities 10^a are adapted to be fed 75 through gates 20.

It is preferable in most cases that the molten metal does not come in contact with any of the metallic filler pieces, and, accordingly, where it is necessary small sand 80 filler pieces, such as shown at 21 may be employed to protect the metallic filler pieces from contact with molten metal.

The drawings illustrate the manner in which two distinct pourings may be carried out to make two distinct sets of castings in 85 one mold, but, in practice, this may be varied as the particular case may require and as will be apparent to those skilled in the art.

The method of assembling the parts is generally as follows. The bottom 1 is laid upon a table of convenient height to permit a workman to either stand or sit while effecting the assembly and thereafter the filler blocks and sand elements 10, 21, 18 and the necessary cores 22 are built up on the bottom 1 after the manner of assembling building blocks. If the proper filler blocks are used as may be designated by the engineering department, the complete assembly of 100 the sand elements and filler blocks will be such that after said assembly is completed, the top wall 2 and the side and end walls 3, 4, 5 and 6 may be set up around the assembly and clamps or other clamping means applied to the end walls to draw them in a direction toward one another. This operation will simultaneously force the top wall toward the bottom wall and the two side walls toward one another as hereinbefore 105 described; for the purpose of contracting the confines of the mold and forcing the filler blocks and sand into tight engagement with one another, so that shifting between the parts is rendered absolutely impossible.

It will of course be apparent that before bringing the top wall 2 into position, sprue sections 17 and a pouring basin suitably lined as at 16 will have been associated therewith.

130

After the parts have been assembled in this manner, the mold is ready for casting and molten metal introduced into the pouring basin will flow through sprue sections 17 and 18 into the runner 19 and thence through several gates into the mold cavities 10^a. After the pouring operation is concluded and the molten metal has set, the pouring basins 14 are removed and a sharp knock will cause the breaking of the sprue so that the parts may be dismantled by reversing the operations described except that the removal of all of the elements of the mold is not essential in the event that it is desired to proceed with further casting operations. Only a sufficient number of these elements may be taken out to permit of the removal of the casting. In practice, the sand elements may, in many instances, be used repeatedly, although any of them which are damaged or broken should be replaced before further pouring. The sprue sections 17 and the linings 16 of the pouring basins may be stock moldings of sand or any other suitable nonwarping refractory material and the particular kind of lining 16 and sprue section 17 may be employed to make a large variety of castings, the particular runners or gating desired being worked out to suit each particular case.

In practice, the lining 16 and the sprue element 17 may be made in sections so as to permit their removal from the solidified pool in the basin and sprue at the conclusion of the casting operation without necessitating the breakage of these refractory parts.

It is highly important in the art of casting to provide for proper venting of the mold cavities, so that the air in the mold and the gases generated during the casting operation may find rapid exit and not spoil the castings. This feature is accomplished in the present invention in a novel and highly efficient manner. Thus, I have shown in Figures 3 and 4, the inner face of one of the end plates or walls of the mold and I have illustrated this part as provided with a large number of grooves or channels 23, which extend transversely and longitudinally of the side plates and form vent channels. All faces of the several filler blocks are also similarly grooved as shown in detail in Figure 5. In practice, the grooves are preferably made semi-circular in cross section and are positioned equidistant apart on all elements of the mold in which they are formed, so that when the elements are assembled within the six walls of the mold, the grooves of adjacent elements will be juxtaposed with one another as shown best in Figures 1 and 2 and form circular passages leading to the exterior of the mold.

In practice, I preferably groove all the faces of all of the filler elements, as well as the interior faces or wall elements or

plates, though I find it unnecessary to groove the sand elements externally. The sand elements are sufficiently porous to permit the passage of air or gases therethrough and such air or gases are free to vent to the atmosphere through the channels or grooves 23 described. The thicker sand elements may if desired be vented in any suitable way as by providing channels for the escape of gases without permitting the exit of molten metal. I have found, however, that for the general run of work the venting of all but the upper sand elements by employing channels therein is not necessary.

The filler blocks employed in the carrying out of the present invention have been specifically referred to as of metal and when so constructed are preferably cored and ribbed as shown to minimize weight. Cast iron, aluminum or any other suitable metal may be employed in their construction, and other materials than metals may be used. For example, pressed gas carbon or any other like, but sufficiently strong and suitable material may be used in lieu of metal for the manufacture of the filler blocks. The presence of the venting grooves in practice makes it immaterial of what the filler blocks are made provided they hold their shape, are not easily damaged and are generally handy.

So far as I am aware I am the first to provide the venting grooves of the character described and know that they may be used to advantage in some of the methods now in vogue. Accordingly, I do not limit the use of these venting grooves to the other details of this invention, but consider them broadly only.

In casting cored objects, suitable cores are employed as described and if desired proper registration of different sections of the mold cavity sand elements may be cast to interfit for the purpose of securing accurate alinement or registration, for example as shown in Figure 6 or in any other suitable way, so that accurate registration will be maintained at all times and the assembly of the sand elements forming the mold cavity may be expedited and facilitated.

From the foregoing detailed description of the invention in its preferred form, the mold is shown as of rectangular formation and the several filler elements entering into the mold construction are shown of light section. This is the preferred manner of practicing the present invention, but I am aware however that shapes other than that shown may be used either as regards the shape of the mold walls or plates, but as to the filler elements and sand elements. The shape of these elements will depend largely upon the article to be cast, though

the rectangular form is preferred whenever possible as the constituent elements of the mold may be more expeditiously and easily assembled.

5 It is recommended, however, that whatever the shape of the plates or walls of the mold, that the outer shape of the sand elements correspond thereto. That is to say, if the walls of the mold form a rectangular 10 box-like chamber, the exterior surfaces of the sand elements should also be of rectangular shape irrespective of the shape of the mold cavity formed therein. This enables the filler blocks or cores of parallel sides to 15 be used to fill out the mold and greatly facilitates the building up of the combination. If the inner face of the mold walls were curved and the outer faces of the sand elements plane or vice versa, difficulty would 20 be experienced in properly filling out the interposed spaces. However, if the outer contour of the sand elements are rectangular and the inner confines of the mold rectangular the intervening space may be readily 25 filled in by rectangular blocks or filler pieces.

I have referred at more or less length to the employment of pouring basins, which, as shown in the drawings, are mounted on 30 the top plate of the mold in a detachable manner. In practice, these pouring basins may be made of different sizes and shapes and may be associated with the mold as occasion may require. This is a far better 35 construction than would be produced by forming the pouring basins integral with the top plate for reasons which will be manifest to those skilled in the art. The attachment of a removable pouring basin to 40 the top plate eliminates special runner boxes and minimizes the height of the mold since the mold would have to be made higher to accommodate its basin if formed directly within the top plate. The top plate may 45 be provided with a number of openings 12, so as to permit pouring basins to be associated with different parts of the top plate in accordance with the positions in which the runners or runner may be placed in the 50 mold, but in the drawings I have shown only two such openings for the purpose of illustration.

Also of special practical importance is the use of the removable sprue sections 17 and 18 and the lining 16, which are preferably made in two parts or split and may be referred to as tubular blocks for use in the pouring sprue or as parts of the risers. When these parts are made in this manner, they may, in many instances, be dismantled 60 after casting without breakage and can then be re-used. If they were formed solid, the sprue would have to be broken off first with the result that these parts would probably 65 be broken and rendered unfit for further use,

I have heretofore described different ways of making up of the sand through the use of dies, molds or otherwise and through the use of core material or other substances. I have found in many instances, where the 70 particular shaping of the casting will permit, that fire brick may be used to advantage and that the same material may be also employed in the sprue sections and in the lining for the pouring basin. Accordingly 75 I do not limit the invention to the specific materials referred to.

The mold of this invention embodies many novel and distinctive features new to the casting art and which collectively may be used to advantage for the production of fine and accurate work and in an economical manner. After the first cost of outfitting the shop with molds embodying the present invention with the filler pieces of assorted 80 sizes, sand forming means, etc., a shop may be run at a relatively low cost, but with astonishing high production. I am aware, however, that certain features of the invention may be employed without necessarily 85 employing them all and accordingly the invention is not restricted to the specific showing of the drawings, but is to be understood as broadly novel as is commensurate with 90 the appended claims.

Having thus fully described the invention, what I claim as new and desire to secure by Letters Patent, is:

1. A casting mold embodying a container, 100 an element of refractory material provided therein with a mold cavity, positioned within the container and of smaller size than the inner confines of the container, metallic filler blocks assembled within the container and filling out the space therein which is not occupied by the refractory mold cavity element, and means for forcing the filler blocks into tight rigid relation with said element.

2. A casting mold embodying a box-like 105 container the interior of which constitutes a substantially closed chamber, a refractory element of smaller size than the inner confines of the container, positioned within the container and provided interiorly with a mold cavity, filler blocks positioned within the container and about the refractory mold cavity element to fill out the space which is not occupied within the container by the mold cavity element, and means for forcing the filler blocks into tight rigid relation with said element.

3. A casting mold embodying a box-like 115 container the interior of which constitutes a substantially closed chamber, a refractory element of smaller size than the inner confines of the container, positioned within the container and provided interiorly with a mold cavity, filler blocks positioned within the container and about the refractory mold 120

- cavity element to fill out the space which is not occupied within the container by the mold cavity element, the walls of the mold cavity element being relatively thin but of sufficient thickness to preclude burning of the filler blocks by molten metal introduced into the mold cavity, and means for forcing the filler blocks into tight rigid relation with said element.
- 10 4. A casting mold embodying a container having a rectangular interior constituting a substantially closed chamber, a chambered element of refractory material of less size than the interior of the container, positioned within the container and provided interiorly with a mold cavity, the exterior of said element being substantially rectangular, and rectangular filler blocks above, beneath, and beside said element for filling out the space which is unoccupied within the container by the chambered element.
- 15 5. A casting mold embodying a rectangular box-like container, a refractory element of less dimensions than the interior confines of the container, positioned within the container and provided interiorly with a mold cavity, rectangular filler elements for spacing the mold cavity element from the top and side walls of the container, and means for introducing molten metal into the mold cavity without its coming into contact with the filler elements.
- 20 6. A casting mold embodying a box-like container, a refractory element of less dimensions than the interior confines of the container, positioned within the container and provided interiorly with a mold cavity, filler elements for spacing the mold cavity element from the walls of the container, a metallic pouring basin exteriorly of the container and having a nonmetallic refractory lining, a feed duct of nonmetallic refractory material leading from the basin through one wall of the box-like container to the inlet of the mold cavity, whereby molten metal may be introduced into the mold cavity from the exterior of the container without coming into contact with the container or the filler elements.
- 25 7. A casting mold embodying a box-like container, a refractory element of less dimensions than the interior confines of the container, positioned within the container and provided interiorly with a mold cavity, filler elements for spacing the mold cavity element from the walls of the container, a metallic pouring basin exteriorly of the container and having a nonmetallic refractory lining, a feed duct of nonmetallic refractory material leading from the basin through one wall of the box-like container to the inlet of the mold cavity, whereby molten metal may be introduced into the mold cavity from the exterior of the container without coming into contact with the container or the filler elements.
- 30 8. A casting mold embodying a container, a plurality of refractory elements, each of which is provided with a mold cavity, positioned within the container and only partially filling the interior thereof, additional refractory elements having runner passages connecting the several mold cavities, and a plurality of filler elements positioned within the container and filling out the space therein unoccupied by the mold cavity and runner elements.
- 35 9. A casting mold embodying a container, a plurality of independent refractory elements, each of which is provided with an independent mold cavity, positioned within the container and only partially filling the interior thereof, a plurality of filler elements positioned within the container and filling out the space therein unoccupied by the mold cavity elements, and an inlet duct leading from the exterior of the container to the inlets of a plurality of independent mold cavities and formed from refractory material, whereby molten metal may be fed to a plurality of said mold cavities without coming into contact with the filler elements.
- 40 10. A casting mold embodying a container, a plurality of independent refractory elements, each of which is provided with an independent mold cavity, positioned within the container and only partially filling the interior thereof, a plurality of filler elements positioned within the container and filling out the space therein unoccupied by the mold cavity elements, and an inlet duct leading from the exterior of the container to the inlets of a plurality of independent mold cavities and formed from refractory material, whereby molten metal may be fed to a plurality of said mold cavities without coming into contact with the filler elements, and said duct being formed of a plurality of sections to facilitate assembly and removal of the parts.
- 45 11. A casting mold embodying a container, a refractory element of non-metallic material positioned within the container and provided with a mold cavity, and a duct leading from the exterior of the container through one wall thereof and through the inlet to the mold cavity, said duct being of non-metallic refractory material and formed of a plurality of longitudinal sections through which molten metal may be poured into the mold cavity, at least one of which longitudinal sections is divided laterally into a plurality of lateral sections to permit removal of said lateral sections from the metal which has hardened therein after pouring without necessitating the disruption of said lateral sections.
- 50 12. A casting mold embodying a con-

tainer, a plurality of refractory elements within the container and providing a plurality of mold cavities, and a metal inlet duct leading from the exterior of the container to the inlets of a plurality of mold cavities and comprising a plurality of assembled longitudinal sections of refractory non-metallic material.

13. A casting mold embodying a container, a refractory element housed within the container and provided with a mold cavity, a pouring basin detachably mounted on the exterior of the container and provided with a refractory lining divided 15 transversely into a plurality of sections, means for normally maintaining the pouring basin and its lining in assembled relation on the container, and a duct of refractory material leading from the pouring 20 basin to the inlet of the mold cavity, whereby the pouring basin and its lining may be dismantled after the pouring operation to facilitate the removal of these parts from such metal as may have solidified in the 25 basin without damage to the basin or its lining.

14. A casting mold embodying a container, a refractory element housed within the container and provided with a mold 30 cavity, a pouring basin detachably mounted on the exterior of the container and provided with a refractory lining divided transversely into a plurality of sections, means for normally maintaining the pouring basin and its lining in assembled relation on the container, and a duct of refractory material leading from the pouring basin to the inlet of the mold cavity, said duct constituting a sprue channel of a plurality of longitudinal sections certain of which are transversely divided into the lateral sections, whereby, after the pouring operation, the pouring basin, together with its lining and the sprue sections, may be readily 40 removed from such metal as may have solidified therein without damage to the divided sections.

15. A casting mold embodying a container, a refractory element positioned within the container and provided with a mold cavity, said element being smaller than the interior of the container, and a plurality of filler elements for filling out the confines of the container, which filler elements have 50 grooved exteriors to permit the escape of air and gases from the mold cavity.

16. A casting mold embodying a container, a mold cavity element positioned within the container, and filler elements between the 55 mold cavity element and the walls of the container for spacing the mold cavity element within the container, said filler elements having grooved surfaces to permit the escape of air and gases from the mold cavity 65 element.

17. A casting mold embodying a container, a porous element positioned therein and having a mold cavity, and non-porous elements for spacing the porous element from the walls of the container, the exterior of 70 said non-porous elements being grooved to permit the escape of air and gases which exit through the porous element from the mold cavity.

18. A casting mold embodying a container, a porous element positioned therein and having a mold cavity, and non-porous elements for spacing the porous element from the walls of the container, the exterior of said non-porous elements being grooved to permit the escape of air and gases which exit through the porous element from the mold cavity, and the container being vented to 75 permit such air and gases to freely escape from the interior thereof.

19. A filler element for use in a casting mold comprising a rigid body, the exterior surfaces of which are grooved.

20. A filler element for use in a casting mold comprising a rigid body having 80 grooved plane surfaces.

21. A filler element for use in a casting mold comprising a rigid rectangular body, the surfaces of which are provided with grooves extending parallel to the edges of 85 each surface.

22. A filler element for use in a casting mold comprising a rigid block, all the surfaces of which are provided with equally spaced grooves.

23. A mold embodying a plurality of separable walls shaped to have wedging engagement with one another when assembled.

24. A mold embodying a plurality of separable walls adapted to be assembled to form a container, those portions of the several walls which engage with adjacent walls being shaped to have wedging engagement with one another.

25. A mold embodying a plurality of separable walls adapted to be assembled to form a closed container, those portions of the several walls which engage with adjacent walls being shaped to have wedging engagement with one another.

26. A mold embodying a plurality of separable walls adapted to be assembled to form a closed container, those portions of the several walls which engage with adjacent walls being shaped to have wedging engagement with one another, and one of the walls being provided with an opening through which molten metal may be passed into the interior of the container.

27. A mold embodying six separable walls shaped to have wedging engagement with one another when assembled and adapted to form a substantially closed chamber.

28. A mold embodying a plurality of separable walls adapted to be assembled to 130

form a container, two oppositely positioned walls being shaped for wedging coaction with the remaining walls, whereby pressure may be applied to said opposite walls to effect a wedging action between these and the remaining walls.

29. A mold embodying a plurality of separable walls adapted to be assembled to form a container, two oppositely positioned 10 walls being so shaped that when forced toward one another they will exert a wedging action on the remaining walls to bring about a contraction of the interior dimensions of the mold and place the contents of the mold 15 under compression.

30. A mold embodying a plurality of separable walls shaped to have wedging engagement with one another when assembled, and the interior faces of which walls are 20 grooved to permit the escape of air and gases.

31. A mold embodying a plurality of separable walls shaped to have wedging engagement with one another when assembled, 25 those portions of the walls which engage with one another being grooved so that the formation of air tight joints is precluded.

32. A casting mold embodying a bottom 30 plate having beveled edges, a top plate having similar beveled edges, a refractory mold element provided with a mold cavity and a plurality of filler blocks assembled in built up relation upon the bottom plate, and below the top plate, and four side plates having 35 their marginal portions beveled to cooperate with the bevels of the top and bottom plates and adapted to cooperate with said top and bottom plates to form a substantially closed container wherein, when 40 pressure is applied to two opposite side walls to force them toward one another, the two other opposite side walls as well as the top and bottom plates will exert pressure on the refractory element and filler 45 blocks to form a tight and rigid assembly.

33. A casting mold embodying a bottom

plate, a refractory element provided with a mold cavity, and a plurality of filler elements grouped upon the bottom plate, a top plate superimposed on the mold cavity element and the filler blocks, and four side walls cooperating with the top and bottom plates to house the filler blocks and mold cavity element in a substantially closed chamber.

34. A mold embodying two oppositely positioned walls the marginal portions of which are dished, and four other walls adapted to extend between the said two opposite walls and having their opposite ends beveled to cooperate with the dished margins of said opposite walls, whereby pressure applied to said two opposite walls to force them toward one another will cause each two opposite walls of the four remaining walls to be forced toward one another.

35. A flask provided externally with a metallic pouring basin having a nonmetallic refractory lining, both the basin and lining being transversely divided into a plurality of lateral sections, and means for detachably maintaining the sections in assembled relation during charging of the flask whereby the sections of the basin and lining may be parted and removed from the sprue 70 without damage to the basin or its lining.

36. A flask provided externally with a metallic pouring basin having a nonmetallic refractory lining, said basin with its lining being detachably mounted on the flask and both the basin and lining being transversely divided into a plurality of lateral sections, means for detachably maintaining the sections assembled with relation to one another and in position on the flask 80 during the charging of the flask, whereby the sections of the basin and lining may be parted and removed from the flask and sprue without damage to the basin or its lining.

In testimony whereof I have signed the foregoing specification.

RICHARD MOLDENKE.
